HARRY P. ROUNDS, OF DETROIT, MICHIGAN.

ATTACHMENT-PLUG.

1,160,531.

Specification of Letters Patent. Patented Nov. 16, 1915.

Application filed October 31, 1913. Serial No. 798,481.

To all whom it may concern:

Be it known that I, HARRY P. ROUNDS, a citizen of the United States, and a resident of Detroit, in the county of Wayne and State of Michigan, have made a new and useful 5 Invention in Attachment-Plugs, of which the following is a specification.

This invention relates to attachment devices for electrical conductors or to devices 10 which are commonly termed attachment plugs, and has for an object to produce a plug which may be easily and quickly inserted into and removed from a socket, without the necessity of twisting the lamp cord 15 attached thereto.

This, and other objects, which will be made apparent throughout the further description of the invention, I attain by means 20 of an attachment or plug embodying the features herein described and illustrated in the drawings accompanying and forming a part of this application.

In the drawings: Figure 1 is a perspective view of a contact carrying element 25 which forms a detail of my invention; Fig. 2 is a perspective view of a collar or eccentric which forms a detail of the present embodiment of my invention; Fig. 3 is a perspective view of the body portion of the plug 30 illustrated; Fig. 4 is a perspective view of the element shown in Fig. 1, but with the shank turned so as to disclose the electrical contacts or terminals of the plug; Fig. 5 is a side elevation of the plug as it appears 35 with the parts in position for being inserted into a socket; and Fig. 6 is a side elevation of the plug as it appears with the parts in the relative positions they occupy when the plug is locked in place in a socket.

40 The plug illustrated as an embodiment of my invention includes three essential elements; a body 7, a contact or terminal carrying element 8, and an eccentric or collar 9, which is rotatably mounted on the shank of 45 the element 8 and is located between the contact carrying end thereof and the body 7.

The body 7 may be formed of any suitable 50 insulating material, such, for example, as hard rubber, and as illustrated, is provided with a central longitudinally extending opening 11, into which the shank of the element 8 is adapted to project, and in which it is adapted to be secured by any suitable means, such, for example, as a set screw 12, 55 which, as shown, is adapted to be screwed into a radially extending aperture formed in

the body and to abut against the shank, and thereby lock it rigidly to the body. The shank of the element 8 is preferably made entirely of insulating material, such as hard 60 rubber, and, as illustrated, consists of a cylindrical or shank portion and a head portion 12'. The shank, as illustrated, is provided with a groove 13 and an aperture 14 for the reception of the separate wires of the 65 lamp cord attached to the plug, but it will, of course, be understood that the shank may be provided with two grooves or two apertures as desired. The head 12' is substantially cylindrical and is preferably formed 70 integrally with the shank, but is located eccentrically thereof, and, if desired, is provided on its periphery with convolutions or threads, which may conform in contour to the convolutions or threads formed in the 75 cylindrical or screw contact 15, which is mounted on the head and extends circumferentially around it. The end contact, or end terminal, 16 is shown secured to the head 12' by means of a contact screw 17, and is located centrally with relation to the head, and is spaced from the screw terminal 15 so that it is insulated therefrom. One of the cords, or wires, 18 is shown extending along the groove 13 and electrically connected to a 80 tongue or extension 19 provided on the screw terminal 15, while the other wire 18' is shown as extending through the aperture 14 and is electrically connected to the end terminal 16 by any suitable means. If desired, 85 the wires 18' may extend around the screw 17, between the terminal 16 and the head portion, and may be forced into contact with the terminal 16 by means of the screw 17.

The collar 9, as illustrated, is substantially 90 cylindrical, although it is desirable to taper it slightly, as shown in the drawings, from the body 7 toward the head 12'. The collar is provided with an eccentrically located, but 95 axially extending opening 21, through which 100 the shank proper of the member 8 is adapted to extend. An arc shape flange 22 extends partially around the outer edge of the collar and projects axially with relation thereto so that it partially surrounds the 105 screw contact 15 of the head 12', when the collar is in position on the shank. The collar is also provided with an annular flange 23, which is located around the end of the collar adjacent to the body portion, and 110 which extends radially. The center of curvature of the flange 22 is located centrally

of the collar, but eccentrically of the opening 21, and the flange projects from that portion of the edge of the collar which is located farthest from the opening 21.

5 In the apparatus illustrated I have shown the body 7 provided with springs 24 for normally forcing the collar 9 along the shank, away from the body, and against the shoulder formed by the construction of the head 10 12' on the shank. As illustrated, the springs are stamped or cut from the ring 25, which is secured in place within an annular groove formed in the end of the body. These 15 springs not only yieldingly press the collar outwardly away from the body, but they also create sufficient friction between the head and the collar to hold the collar in the positions to which it may be turned so that it will not shift its position by reason of its 20 own weight.

In assembling the separate parts of the plug, the wires 18 and 18' are attached to their respective terminals in the usual manner, or as previously described. The collar 25 9 is then rotatably mounted on the shank proper of the member 8 and the body 7 is moved to position over the shank with the wires extending through the end of the opening formed in the body as shown in 30 Figs. 5 and 6. The set screw 12 is then driven home so that it rigidly locks the shank and the body together. This completes the assembling operation of the plug.

In preparing the plug for insertion into a 35 socket, the collar 9 is turned about the shank so that it occupies a position substantially concentric with the head 12', in which the flange 22 contacts with the screw terminal 15. It will be understood that the eccentricity of the head with relation to the shank proper of the member 8 is substantially 40 equal to the eccentricity of the collar with relation to the opening 21 of the collar and that the curvature of the flange 22 is substantially 45 equal to the curvature of the peripheral face of the screw contact 15. It will also be understood that the flange 22 is of such length circumferentially of the collar that it forms a stop for the collar by its 50 engagement with the head when the collar is moved to an eccentric position with relation to the head.

In securing the plug in place in the socket, it is inserted into the opening of the socket 55 and pressed inwardly relatively to the socket, so that its contact 16 engages the inner or central contact of the socket and so that the tapered peripheral face of the collar 9 is engaged by the cylindrical or threaded 60 terminal of the socket. It will be understood by reference to the drawings that the body is preferably so located on the shank portion of the member 8 that the springs 24 normally maintain a clearance between it 65 and the collar so that the collar can be

moved away from the head 12' by its engagement with the socket when the plug is forced into place. With such an arrangement the frictional grip between the collar 9 and the head 12' will be broken, and the friction between the collar and the engaging terminal of the socket will be greater than that between the collar and the shank. While the plug is thus pressed into the socket, the body 7 is turned to the right, 75 relatively thereto, something less than half a turn. This causes the head to move eccentrically of the collar and away from the flange 22, since the collar is held stationary by the socket and since the shank is rigidly 80 secured to the body. The grooved or threaded surface of the cylindrical terminal 15 of the head is therefore forced into engagement with the threads of the cylindrical terminal of the socket, and consequently completes 85 the electrical circuit, and also locks the plug in place within the socket. The clearance between the collar and the body 7 also comes into play during the operation of turning the terminal 15 into engagement with the cylindrical terminal of the socket, since it permits the head 12' to move longitudinally of the collar an amount sufficient to insure an effective engagement between the threads of the terminal 15 and the threads of the 90 socket terminal. In releasing the plug, it is turned to the left; that is, in an opposite direction from that which it is turned in securing it to the socket. This moves the head to the position shown in Fig. 5, or, in other 100 words, to a position substantially concentric with the collar 9 and therefore releases it from the engagement of the threads of the cylindrical terminal of the socket, so that it may be easily withdrawn from the socket. 105

In accordance with the United States patent statutes, I have illustrated what I now consider the preferred embodiment of my invention, but I desire it to be understood that various changes, modifications, substitutions, additions, and omissions may be made in the apparatus illustrated without departing from the spirit and scope of my invention as set forth by the appended claims. 110

I claim—

1. A terminal plug of the character described, comprising a body, a shank located concentrically on the body, a terminal carrying element eccentrically mounted on the shank, an end terminal mounted on said element, a side terminal mounted on said element and insulated from the end terminal, and a collar having an eccentrically located shank engaging opening formed there- 120 in rotatively mounted on the shank. 125

2. A plug comprising a body, a shank mounted on the body and having an eccentrically located terminal-carrying head, and a collar rotatively mounted on and movable 130

- around the shank and located eccentrically with relation to the shank.
3. A plug of the character described, comprising a body, a shank rigidly mounted on the body, a terminal-carrying head carried by the shank and located eccentrically with relation thereto, and a collar, having an eccentrically located shank engaging opening, rotatively mounted on the shank, between the body and the head, and movable around the shank from a concentric to an eccentric position with relation to the head.
4. A socket-engaging plug of the character described, comprising a body, a shank rigidly mounted on the body and having an eccentrically located terminal-carrying, socket-engaging head, and socket-engaging means, having a tapered peripheral surface and an eccentrically located shank engaging opening formed therein, rotatively mounted on the shank and movable around the shank to force the head into locking engagement with a socket into which the head and the means are inserted.
5. A plug comprising a body, a shank rigidly mounted on the body and having a terminal-carrying head eccentrically mounted thereon, a collar rotatably mounted eccentrically on the shank between the head and the body, and having an axially projecting flange partially encircling the head, and an annular radially projecting socket engaging flange formed adjacent to the body, and means for yieldingly forcing the eccentric along the shank toward the head.
6. A terminal plug comprising a body, a shank mounted on the body, a terminal carrying member mounted on the shank and located eccentrically with relation thereto, and a socket-engaging collar having an eccentrically located shank-engaging opening formed therein, rotatively mounted on the shank between the body and the head and movable about the shank to eccentric and concentric positions with relation to the head, and provided with an axially projecting flange partially encircling the head.

In testimony whereof, I have hereunto subscribed my name this 28th day of October, 1913.
